Primary Examiner — Marianne N Pandozzi(74) Attorney, Agent, or Firm — Jonathan E. Grant; Grant Patent Services(57) CLAIM

I claim the ornamental design of the dispenser jar, as shown and described.

DESCRIPTION

FIG. 1 is a perspective view of a dispensing jar showing my new design;

FIG. 2 is a left side view thereof;

FIG. 3 is a right side view thereof;

FIG. 4 is a rear view thereof;

FIG. 5 is a front view thereof;

FIG. 6 is a top plan view thereof;

FIG. 7 is a bottom plan view thereof; and,

FIG. 8 is another perspective view thereof.

The broken lines in the drawing depict portions of the dispenser jar that form no part of the claimed design.
